UNITED STATES PATENT OFFICE

147,862

DESIGN FOR A TAXICAB CRUISING LAMP

Charles Dee Nelson, Jr., Arlington, Va.

Application March 10, 1947, Serial No. 137,483

Term of patent 14 years

(Cl. D48—16)

To all whom it may concern:

Be it known that I, Charles Dee Nelson, Jr., a citizen of the United States, residing at 4828 Lee Boulevard, in the county of Arlington and State of Virginia, have invented a new, original, and ornamental Design for Taxicab Cruising Lamp, of which the following is a specification, reference being had to the accompanying drawing, forming part thereof.

Fig. 1 is a perspective view of a taxicab cruising lamp, showing my new design;

Fig. 2 is a top plan view thereof;

Fig. 3 is a side view thereof.

I claim:

The ornamental design for a taxicab cruising lamp, as shown.

CHARLES DEE NELSON, JR.
